UNITED STATES PATENT OFFICE.

SAMUEL GEE, OF PROVIDENCE, RHODE ISLAND.

DESIGN FOR A NUMBER-DISPLAY CASING.

44,237.

Specification for Design. Patented June 24, 1913.

Application filed February 3, 1913. Serial No. 746,058. Term of patent 7 years.

To all whom it may concern:

Be it known that I, SAMUEL GEE, a citizen of the United States, residing in the city and county of Providence, State of Rhode Island, have invented a new, original, and ornamental Design for a Number-Display Casing, of which the following is a specification, reference being had to the accompanying drawing, forming part thereof.

Figure 1— is a plan view of the casing.

Fig. 2— is a front elevation of my improved design. Fig. 3— is an end elevation of the same.

I claim:

The ornamental design for a number-display casing as shown.

SAMUEL GEE.

Witnesses:

HOWARD E. BARLOW,
E. I. OGDEN.
